LANTERN

Roland D. Evans, Granite City, Ill., assignor to
Handlan-Buck Manufacturing Company, St.
Louis, Mo., a corporation of Missouri

Application June 9, 1934, Serial No. 729,788

3 Claims. (Cl. 240—38)

This invention relates generally to lanterns, and more specifically to a hand lantern adapted particularly for use on trucks, railroad cars, and other mobile structures, the predominant object 5 of the invention being to provide a hand lantern which is of such unique construction and arrangement that it is capable of performing its intended function in a very efficient manner.

It is well known by persons familiar with such 10 matters that motor trucks frequently are provided with hand lanterns which are suspended in positions on the trucks to provide lights required by regulations of States and municipalities. In some cases these lanterns are used 15 to avoid having the batteries of the trucks unduly drained by a great number of electric lights on the trucks, while in other cases regulations of States and municipalities require that lights in addition to those forming parts of the electrical 20 lighting systems of the trucks be provided so that the trucks would be equipped with adequate lights in the event the electrical lighting systems of the trucks failed.

The lantern disclosed herein is so constructed 25 and arranged that it may be suspended by its bail from a part of a truck or other mobile structure, and because of the construction of the lantern and the offset arrangement of the bail the lantern hangs in a substantially straight position 30 and is subjected to a minimum of swaying movement during travel of the mobile structure on which it is mounted. Also, because of the particular construction of the improved lantern, it is sufficiently sturdy and durable to withstand the 35 rough usage to which a lantern is subjected when used on a vehicle or other mobile structure.

Fig. 1 is a side elevation of a lantern made in accordance with this invention.

Fig. 2 is a rear elevation of the lantern shown 40 in Fig. 1.

Fig. 3 is a plan view of the lantern illustrated in Figs. 1 and 2.

In the drawing, wherein is shown for the purpose of illustration, merely, one embodiment of 45 the invention, A designates the improved lantern generally. The lantern A includes a font B, a hood C, and a chimney D supported by an annular portion E located at the upper portion of the font B. The lantern is also provided within 50 the chimney D with a suitable burner (not shown), the wick of which is regulated by the wick-adjusting element F.

The guard frame of the improved lantern comprises a horizontal base ring 1, a horizontal top 55 ring 2, and a pair of intermediate horizontal

guard rings 3. The horizontal, intermediate guard rings 3 are of slightly greater diameter than the base and top rings 1 and 2. The guard frame includes also a plurality of vertically disposed guard elements 4, 5, 6, and 7 in the form 5 of rods or sections of heavy wire, said vertical guard elements at the opposite ends thereof being bent around the base and top rings so that said bent portions of the vertical guard elements closely embrace the base and top rings. The vertical 10 guard elements are each soldered, welded, or otherwise securely fixed to the flange B' of the lantern font B, and also these vertical guard elements are each soldered, welded, or otherwise secured to the horizontal guard rings 3 at the inside face portions thereof. Thus the various 15 members which comprise the guard frame of the improved lantern are securely attached together to produce a strong, unitary construction, and said guard frame is rigidly anchored to the lantern proper so as to constitute same an integral 20 part of the complete lantern structure.

The vertical guard elements 6 and 7 are provided with eyes 8 to which a bail 9 is attached. The vertical guard elements 6 and 7 are located at 25 the rear of the lantern, and the bail when disposed in a vertical position, as shown in Figs. 1 and 2, is located immediately adjacent to the rear of the lantern. By offsetting the bail from the center of the lantern, as bails of lanterns were 30 heretofore arranged, to a position adjacent to the rear of the lantern, the improved lantern may be suspended in a substantially vertical position. Also, because the guard frame of the lantern does not extend outwardly beyond the 35 outer edge of the hood C of the lantern, there will be very little rolling movement of the lantern with respect to a moving support against which it hangs as would be the case if the vertical guard elements of the guard frame were 40 bowed outwardly, as was usually the case heretofore. Finally, the simply constructed and durable guard frame is capable of withstanding the rough usage to which a lantern is subjected when 45 mounted on a mobile structure.

I claim:

1. A hand lantern comprising a font, a hood, a chimney interposed between said font and said hood, a guard frame arranged to surround said chimney, and a bail for carrying the lantern or suspending same from a support, said bail being connected to said guard frame so that it is disposed adjacent to one side of the lantern, whereby the lantern may be suspended in a substantially vertical position in contact with a ver- 55

- tically disposed support, said guard frame comprising substantially straight, vertically extended guard elements to certain of which said bail is attached and horizontal guard rings secured to 5 said vertically extended guard elements, said vertically extended guard elements being secured to said font, and said horizontal guard rings being of no greater diameter than the greatest diameter of said hood.
- 10 2. A hand lantern comprising a font, a hood, a chimney interposed between said font and said hood, a guard frame arranged to surround said chimney, and a bail for carrying the lantern or suspending same from a support, said bail being 15 connected to said guard frame so that it is disposed adjacent to one side of the lantern, whereby the lantern may be suspended in a substantially vertical position in contact with a vertically disposed support, said guard frame comprising substantially straight, vertically extended guard 20 elements to certain of which said bail is attached, a base ring located beneath said font, a top ring located at the lower portion of said hood, said vertically extended guard elements being attached 25 at their opposite ends to said base and top rings, and intermediate rings surrounding said chimney and fixed to said vertical guard elements, said vertically extended guard elements being secured to said font.
3. A hand lantern comprising a font, a hood, a chimney interposed between said font and said hood, a guard frame arranged to surround said chimney, and a bail for carrying the lantern or suspending same from a support, said bail being connected to said guard frame so that it is disposed adjacent to one side of the lantern 5 whereby the lantern may be suspended in a substantially vertical position in contact with a vertically disposed support, said guard frame comprising substantially straight, vertically extended guard elements to certain of which said bail is 10 attached, a base ring located beneath said font, a top ring located at the lower portion of said hood, said vertically extended guard elements being attached at their opposite ends to said base and top rings, and intermediate rings surrounding 15 said chimney and fixed to said vertical guard elements, said vertically extended guard elements being secured to said font and said base, top, and intermediate rings being of no greater diameter than the greatest diameter of said hood. 20 25
